AND ONE-FOURTH TO ARTHUR J. MASON, BOTH OF CHICAGO, ILLINOIS.

CHARGING DEVICE FOR BLAST-FURNACES.

No. 890,569.

Specification of Letters Patent.

Patented June 9, 1908.

Application filed January 12, 1905. Serial No. 240,731.

To all whom it may concern:

Be it known that I, ARTHUR G. MCKEE, a citizen of the United States, resident of Cleveland, county of Cuyahoga, and State of Ohio, have invented a new and useful Improvement in Charging Devices for Blast-Furnaces, of which the following is a specification, the principle of the invention being herein explained and the best mode in which 5 I have contemplated applying that principle so as to distinguish it from other inventions.

My invention relates to apparatus for charging blast furnaces with coke, iron ore, limestone and other materials with which the 10 furnaces are to be supplied.

The object of said invention is to effect the distribution of these materials in the crater of the furnace as uniformly as possible.

There is no method known to the art by 20 which the several charging materials can be placed in the furnace without more or less segregation of the coarser from the finer and the heavier from the lighter particles of each bucket or skip-load, with the usual result 25 that, more coarse material going to one point or points than to others, the column of stock at such points of the furnace offers less resistance to the passage of the gases, or draft, making that side of the furnace much hotter 30 with a higher zone of fusion, a higher rate of combustion and reduction, greater abrasion due to the high velocity of gas and stock, and a consequent early destruction of the furnace lining on that side. On the other 35 hand points receiving the larger proportion of the fine material will have their voids largely filled with this fine material. This will result in a greater resistance to the passage of the draft, and a consequent lower 40 zone of fusion, lower temperature, sticking of the stock to the walls, "slips," irregular and poor grades of iron, and other ills well known to furnace men.

My invention overcomes the ills above referred to by such a manner of handling the successive charges or skip-loads as secures their substantially uniform distribution, as respects coarse and fine particles, around the 45 axis of the furnace; and in the accompanying drawing I have illustrated one practical form of apparatus whereby the object and advantages of the invention may be attained; said drawing representing a vertical 50 axial cross-section of a blast furnace top of a well known form now in general use as ar-

ranged in accordance with my invention, portions of the apparatus being broken away and portions cut by the plane of section being shown in elevation.

Referring to the drawing, the mechanism 60 therein illustrated embodies, in addition to other parts hereinafter described, automatic means for raising the material to the top of the furnace in a skip A, such means being arranged to dump the contents of the skip at a 65 point above such top and fixed relatively thereto. These means *per se* do not form any part of my invention, and may be any one of the forms of mechanism adapted to accomplish this purpose which are well 70 known to those skilled in the art.

In the usual opening in the top of the furnace B is secured a fixed hopper B¹, which has its lower or bottom opening controlled and normally closed by a bell C¹, while its top 75 opening is covered by a frusto-conical cap B², upon which is secured a receptacle C¹, which may be made in any of a number of suitable forms, but whose lower opening is controlled and normally closed by a bell, C². This receptacle C¹ is of such a size as to be capable of containing but one or two skip-loads of material at one time; and in the said construction heretofore used, where such receptacle has been of stationary form, it has been found 80 that the greater portion of large lumps of material was always deposited in the side of the receptacle opposite to or nearly opposite to the point of dumping (depending upon the particular form of the receptacle C¹ used in 85 each case), and the greater portion of the fine particles and dust was always deposited at a point near or immediately below the dumping point. This segregation of the coarse and fine material has heretofore been continued 90 in much the same proportion during its passage through the lower hopper and furnace, with the result that the gases found an easier 95 passageway up the side of the furnace containing the preponderance of lumps, with the resulting bad working of the furnace and 100 an early destruction of its lining above described.

Assuming the receptacle C¹ and the hopper B¹ to be closed by their respective bells, my 105 device operates as follows: The skip-loads of material are dumped into the receptacle C¹ successively at any desired intervals, each charge distributing itself automatically over the bell C² and around the vertical axis of the 110

receptacle C¹, the coarser lumps finding lodgment on the side opposite the skip, and the dust and finer particles tending to collect on the side adjacent to the skip. After each skip-dumping operation, the said receptacle is partially rotated by a driving rope or cable c⁷ passing around a sheave c⁶ integral with or secured to the receptacle C¹, or by any other suitable and equivalent rotating mechanism, and the bell C² is lowered to deposit the load into the hopper B¹ by means of a lever E that is fulcrumed on a suitable fixed support F and is provided with a motor G and a counterweight E¹ for counter-balancing to a greater or less extent the weight of the parts suspended from the other end of the lever E. The bell C² is suspended from a tube C⁸ to whose upper end is secured a bearing disk c³ having an anti-friction ball-bearing, as shown, in the yoke C⁹, which latter is suspended from the end of lever E. These successive partial rotations of the said receptacle C¹ are made of a length increasing successively by equal increments, so that the lumpy portion of each skip-load, after the latter has been deposited in the receptacle C¹, is deposited in the hopper B¹ at a point differing from that at which such lumps of the immediately preceding load were deposited. It will therefore be seen that the large lumps and the finer material are successively deposited at different and successive points in the hopper B¹, the coarse and fine parts of the various loads overlapping, and by using a proper schedule of variations in the amount of rotation, the irregular and unequal distribution heretofore unavoidable in the hopper B¹ and the furnace, is equalized and made uniform to an extent heretofore impossible. When the hopper B¹ is filled to the desired extent, the bell C² is lowered to deposit the contents of the hopper B¹ in the furnace through the agency of a lever E² fulcrumed on a suitable support F², connected with the bell C² by a rod c⁴ extending through the tube C⁸ and provided with a motor G and a counterweight E¹. It will be observed that the operation of the mechanism described is such that each skip-load of material is distributed in the receptacle C¹ in a layer concentric with the furnace. This annular or ring-like arrangement of each skip-load of the material is maintained as it is lowered into the hopper B¹ and thence into the furnace, which result is especially desirable, as each skip-load is thus spread over the crater of the furnace in a thin layer, and thus offers the best conditions for intimate contact and easy chemical reaction with the adjacent layers. The distribution of the limestone or flux in this manner is required in order that a uniform slag may result; but if the operator, for any reason, desires to make the layers of other materials thicker, this can readily be accomplished by charging two or more skip-loads of

the one material in succession. By this arrangement any un-uniform conditions in the furnace can be equalized by means of individual portions in any manner and at any time desirable, so that equal segments of the material in the furnace after any one series of "rounds" has been charged therein, or when the initial point is again reached, will contain substantially equal volumes of voids.

I am advised that a rotatable spout has heretofore been employed for controlling the distribution of the furnace charge, but my invention embodies certain advantageous features not found in a device of such character. For instance, each skip-load is first deposited in the upper receptacle in a layer concentric with the furnace, and then is distributed in the lower hopper and finally in the furnace, with the result that the several materials are uniformly distributed in much finer layers than is possible with the device mentioned. This is especially desirable in order that the limestone may be mixed as intimately as possible with the other charged materials, thus facilitating the chemical reaction incident to the formation of slag. In the device employing the discharging spout this is impossible, as all of each skip-load is deposited at one point in the circumference of the furnace, and the deposit of flux throughout the entire circumference of the furnace is not accomplished until several "rounds" have been charged. The uniform distribution of the fine and coarse particles throughout the entire cross-section of the furnace is also more perfectly and effectively secured than is possible through the agency of a rotatable spout.

I claim:

1. In charging devices for blast furnaces, the combination with means for forming a charge of stock comprising a plurality of portions each distributed in a layer concentric with the furnace, the positions of similar parts of different portions being varied; of means for introducing such charge as a whole into the furnace.

2. In charging devices for blast furnaces, the combination of a receptacle; means for depositing portions of the charging material therein at intervals of time; means for shifting the position of said deposited material; and means for distributing each portion over the entire crater of the furnace.

3. In charging devices for blast furnaces, the combination of a receptacle, means for depositing portions of the charging material therein at intervals of time, each such portion being deposited in a ring the center of which coincides with the projected axis of the furnace; means for shifting the position of said deposited material in a horizontal plane around said axis; and means for introducing into the furnace a charge comprising a plurality of such portions.

4. In charging devices for blast furnaces, the combination of a hopper; means for distributing each portion of stock at intervals therein; and means for varying as desired, 5 relatively to the furnace-circumference, the positions of similar parts of different portions.

5. In devices for uniformly distributing stock in blast furnaces, the combination of a hopper; means for forming therein successive 10 charges of stock each comprising a plurality of portions, each such portion being distributed in said hopper in a ring concentric with the furnace; means for introducing said charges successively into the furnace; 15 and means for causing a plurality of said charges to contain substantially equal volumes of voids.

6. In charging devices for blast furnaces, the combination of a hopper of a capacity to 20 receive and hold a charge of stock comprising a plurality of portions; means for introducing into the hopper said portions separately and each distributed over the entire surface of the hopper; means for depositing 25 where desired, relatively to the furnace-circumference, the major part of the coarse material of different portions; and means for

introducing into the furnace the charge of stock as a whole.

7. In an apparatus for charging centrally 30 filled blast-furnaces, the combination with a stationary receptacle having a lower orifice centrally coincident with the vertical axis of the furnace and opening directly into the latter, of a bell to seal said orifice movable 35 toward and from the latter, a superposed distributing receptacle having a lower orifice opening into said stationary receptacle, a bell movable toward and from said last-named orifice to seal the same, means for introducing a charge of stock to said distributing receptacle in such a manner that said charge occupies substantially the entire cross-sectional area of the latter, and means for rotating said distributing receptacle whereby 40 to distribute around the vertical axis of the furnace the errors or irregularities of successive charges.

Signed by me, this 9th day of January 1905.

ARTHUR G. MCKEE.
